UNITED STATES PATENT OFFICE.

JACOB SEEBOLD, OF NEW BERLIN, PENNSYLVANIA.

GRAIN-SEPARATOR.

Specification of Letters Patent No. 25,677, dated October 4, 1859.

To all whom it may concern:

Be it known that I, JACOB SEEBOLD, of New Berlin, in the county of Union and State of Pennsylvania, have invented a new and useful Improvement in Grain-Separators; and I do hereby declare that the following is a full, clear, and exact description of the same, reference being had to the annexed drawing, forming part of this specification, in the several figures of which similar characters of reference denote the same part.

The figure represents a side view of the machine.

15 The nature of my invention consists in attaching to the thresher a perforated separator by means of a rocking frame, or shaft having an arm on each side to which the separator is fastened, the arm on one side is longer and has a slot, to which is attached by a pin through the slot, a rod connecting with a wheel in front of the thresher. The separator is supported at the other end on a similar rocking frame attached to it by two 20 short arms and having a spiral spring extending from one arm of the frame to the separator to assist in the movement of the separator.

25 The details are as follows:
30 In the drawing, A is the thresher, B the

separator supported at one end on rocking shaft *c* having a slotted arm *b* which is connected by rod *d* to wheel *W*, the slot allowing it to be moved along the arm *b* and increasing or lessening the rapidity of the motion of the separator, *f* is the rocking frame on which the other end of the separator rests, and *S* is the spiral spring. So that the revolution of wheel *W* gives a reciprocating movement to the separator by means of its 35 rod connection *d* with the arm *b* of shaft *c* to which the separator is attached, the spring *S*, also assisting in the motion of the separator. By moving the rod *d* toward the end of arm *b*, in the slot, the arm is 40 lengthened and the speed of the movement of the separator is increased.

45 I claim—

Attaching the separator to the thresher by rocking frames *c*, and *f*, in combination 50 with wheel *W*, rod *d*, slotted arm *b*, and spring *S* for producing its reciprocating movement substantially as described.

In testimony whereof I have hereunto signed my name before two subscribing 55 witnesses.

JACOB SEEBOLD.
